RESETTING ATTACHMENT FOR FLUORESCENT LAMP STARTERS

Filed July 30, 1949

FIG. 2.

UNITED STATES PATENT OFFICE

2,612,578

RESETTING ATTACHMENT FOR FLUORESCENT LAMP STARTERS

Lafe Stueland, Alameda, Calif.

Application July 30, 1949, Serial No. 107,779

6 Claims. (Cl. 200—172)

1

This invention relates to starters for fluorescent lamps and more particularly to starters of the manually reset type. For many years it was necessary to replace such starters when they had burned out due to faulty line conditions such as low voltage which resulted in excessive heating of the starter unit and especially the series resistance therein. More recently there has been on the market a starter unit comprising the usual components of neon lamp and series connected resistance, and in addition a bimetal or other thermally actuated switch member effective to break the series circuit in the event of the abnormal line conditions referred to and also to disconnect at once and permanently a defective lamp from the line without the tell-tale blinking previously encountered. Starters of this type have also been provided with a resetting arm as one member of the switch of which the bimetal member is the other, so arranged that the resetting arm snaps outwardly away from the bimetal member upon deflection of the latter. Such outward movement is accomplished by presetting the resetting arm so that it is normally biased outwardly and is maintained in circuit closing position only by the bimetal member whose end is formed with a retaining hook, for example.

Above the resetting arm and contacting the same is usually provided a resetting button disposed in a central aperture of the starter casing and adapted to move the arm past the retaining hook mentioned into latched position, closing the circuit again when said button is pushed inwardly. The foregoing components are well known in the art but a brief understanding of their interrelation is necessary for an understanding of the action of and the particular utility of the invention now to be described. It is to be remembered, therefore, that it is the actuation of the resetting button to again complete the circuit within the starter that this invention is particularly concerned.

It is well known also in the servicing of fluorescent lamps, their sockets, starters, etc. that considerable inconvenience attaches due to the fact that such lamps are usually mounted high above the work space, close to the ceiling as a rule and accessible only by the use of a ladder and frequently the moving of furniture, equipment, etc., to properly position the ladder. The same difficulty is presented in operating the resetting button earlier referred to. Although such button projects through the disc-like cap of the starter to cover and such cap is frequently dish-shaped to facilitate manual operation of the button, the re-

2

setting operation is, nevertheless, attended with considerable inconvenience. One of the chief difficulties arises from the customary location in most fluorescent light fixtures of the starter beneath the lamp when the latter is positioned within its sockets so that the lamp must be removed in order for the resetting button to be manually accessible for the resetting operation. This objection is quite serious and time-consuming in practice, since in large installations several of the personnel are frequently continuously occupied in renewing such components and in resetting such buttons to their circuit closing positions. Another objection is to be found in the uncertainty which attends the resetting operation. The button is so small, that even if it were accessible when the lamp is in position, there is no way to be certain that the latching operation has been accomplished, since the lamp may light on the first reclosing of the circuit, while the release of the button at this point may allow the resetting arm to return to its open circuit position. It is toward the elimination of such difficulties that the present invention is directed.

Accordingly, it is an object of the present invention to provide an attachment for the manually reset button of a starter of a fluorescent lamp that may be actuated despite the obstruction offered by the presence of the lamp.

Another object of the invention is to provide an attachment of the character described by which the starter may be reset by an operator from the floor by using a suitable rod and without removing the lamp.

A further object of the invention is to provide an attachment of the character described which is certain in its action in relatching the manually reset starter.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and description may be adopted within the scope of the invention as set forth in the claims.

Reference is now made to the drawing wherein: Figure 1 is a perspective view of one end of a standard fluorescent lamp holder or socket assembly with starter and having installed therein with one form of the present invention;

Figure 2 is a side elevation of a fluorescent lamp mounting showing another embodiment of

my invention applied to alternative positioned starters of such lamp mounting;

Figure 3 is a perspective view of the manually reset fluorescent lamp starter described herein together with still another embodiment of my invention for facilitating the resetting operation, the container for the starter being largely broken away to aid in understanding the cooperation of the inner starter components;

Figure 4 is a plan view of the embodiment of Figure 3 with the central mounting for my button actuator centrally cut away to show the operation thereof; and

Figure 5 is a perspective view of still another embodiment of my invention as applied to a 15 starter of the type hereinafter more fully described.

For a more complete appreciation of the present invention and its utility, it is preferred at this point to furnish a brief description of a 20 manually reset starter as earlier mentioned, and which is shown in perspective on the drawing. Such a device is shown in Figure 3 wherein the dish-shaped cap portion 1 and cylindrical wall portion 2 of a casing 3 for the starter are shown as broken away to more clearly disclose the components inwardly of the casing. Upon an insulating disc 4 closing the open end of the casing 3 is mounted a pair of small angle brackets 5 only one of which is visible in Figure 3. Brackets 5 are spaced apart and serve to support and maintain upright within the casing 3 an elongated strip of insulating material 6 having mounted thereon by means of rivets 7 and 8 extending therethrough a thermal responsive element, preferably in the form of a bimetal strip 9. The bimetal strip extends in the same direction as the longitudinal axis of the casing 3 and has formed on its end opposite from the rivets 7 and 8 a hook 10 with which the adjacent end of the strip is normally biased closely against the insulating material 6 when the starter and strip 9 are no warmer than the ambient temperature.

Below said strip 9 and slightly offset therefrom is mounted a current type resistor 11 having its central contact wire 12 surrounded by and united to a connecting strip 13 which is doubled thereover and fixed to the strip 9 by means of the rivet 7. The lower connector 14 of the resistor 11 is connected to one of the angle brackets 5 by means of a rivet 15 passing through the strip 13 and joined to said bracket. Beneath said insulating disc 4 contactor posts having enlarged head portions are mounted in electrical and mechanical relationship with said brackets, one of said posts 16 being visible at the lower end of the casing 3 of Figure 3.

On the insulating disc 4 and on the opposite side of the strip 6 of insulating material from the resistor 11 and bimetal strip 9 is mounted a neon lamp 17, having one of its terminals connected to the other bracket and contactor post of the disc 4 but not visible in Figure 3 due to the angle of perspective. The other terminal of the lamp 17 is connected to an electrical stud 18 which extends through the insulating strip 6. The latter strip is slotted at two locations adjacent the upper end thereof, centrally thereof as indicated at 19 and also at the upper corner of the strip as at 20. Slots 19 and 20 serve as guideways for a spring-biased member 21 mounted on stud 18 and extending upwardly along the insulating strip 6, thence inwardly through said slot 20, about the upper end of neon lamp 17, and thence through the slot 19 and

5 to a latched position beneath the latch 10 of the bimetal strip 9 as is clearly shown in Figure 3. It will be observed, further, that the spring member 21 which may be of small wire or rod, for example, is formed as a loop above the neon lamp 17 and one leg of such loop passes directly beneath a resetting button 22, retained in an aperture 23 centrally disposed in the end cap 1. Thus it will be seen that upon overheating of the bimetal strip 9 as by excessive current passing therethrough, the strip will bend outwardly away from the insulating strip 6 carrying with it the latch 10 so that the end of the spring-biased member 21 is free to spring upwardly away from such latch to open the circuit already described. Upon later pressing the resetting button 22, however, when the bimetal 9 has cooled and returned to its normal position shown in Figure 3, the loop of spring member 21 will be pressed downwardly, carrying with it the end portion which is adapted to slide beneath the latch portion 10 and be retained thereby.

Having described in some detail the starter with which the present invention is concerned, reference is now made to Figure 3 for its showing of the interrelation of the present improvement and the manually reset starter. Above the end cap 1 is disposed the bridge member 24 which is formed as an elongated strip of flat material disposed diametrically across said cap and having downturned end portions, 25 and 26 which may terminate in a plurality of spaced teeth 27, 28 for gripping the milled portion 29 of the cylindrical casing wall 2 to hold said bridge member 24 and casing for the starter in rigid relationship. At the junctions of the downturned end portions 25 and 26 with the central portion of bridge member 24, slots 30 and 31 are provided to serve as journals or fulcrums for a 30 rod-like, button actuating member 32 having a configuration now to be described. As will be seen from Figures 3 and 4 the actuating member 32 includes an elongated handle portion 33 extending upwardly (Figure 3) which is, of course, 35 opposite to its position when mounted in an installed lamp assembly, a laterally offset portion 34 which serves to space the handle portion 33 from the vertical axis of the starter casing, a central, button actuating portion 35, suitable bearing portions for disposition within slots 30 and 31, and a crank portion 36 for increasing the mechanical advantage of the handle 33. The operation of the actuating member 32 will 40 be observed as effective to press downwardly upon the button 22 when the handle portion 33 (Figure 3) is moved toward an observer. Also the handle portion is considerably offset and out of the way of the fluorescent lamp itself, when the latter is in position in the fixture. Viewed from below it is seen to be in position for easy rotation to its resetting position as by 45 means of any suitable rod (not shown) for the purpose, and to be carried through its full arcuate movement to insure relatching of the end of the spring member 21.

In Figure 1 is shown the advantageous positioning of the actuating member with respect to a conventional end assembly of a fluorescent lamp fixture and embodying a modified form of the invention. Herein the lamp 37 having end cap 37a mounted in the socket 37b beneath the reflector 38 is shown as vertically beneath the starter 2 which is mounted in its socket 38a. The form of the invention shown in Figure 1 dispenses with the bridge member 24 by forming the actuating member 32a as a single wire or rod

member doubled back on itself at 39 to provide a handle portion 33a outwardly offset and right angularly disposed with respect to a body portion which spans the starter casing 2 approximately diametrically and is formed centrally thereof in the shape of a closed loop for engaging the resetting button 22 to move the same to closed position. The remote end 40 of the actuating member 32a is reversely bent and is terminally pointed to seat firmly upon the milled surface 29 of the casing 2, while the near end of the member 32a is closely looped about the body of the member at 41, bent upwardly and inwardly to engage its pointed terminus with the face of the casing 2 opposite the end 40. It will be seen, therefore, that the form of the invention shown in Figure 1 embodies an attachment that may be readily attached to and removed from a fluorescent lamp starter of the type described. The mounting of the attachment upon the casing also bears some resemblance to that shown in Figure 5 and described more particularly hereinafter.

The form of the invention shown in Figure 2 resembles that of Figure 1 as to its mounting upon the starter casing but is further characterized by the provision of an elongated and closed loop 41a on the actuating member which is easier to engage by a suitable hook attached to the manipulating rod referred to in the detailed description of Figure 3 when the starter is located on the end wall of the fluorescent fixture or on a side wall of the fixture above the lamp as is indicated by the dotted outline of Figure 3. Herein, the remote end 40b of the actuating member is pointed to seat upon the milling 29 of the casing 2, while the other end is bent about the body of the member at 41b to provide the loop 41. The contact loop is provided as before and is slightly offset to engage the resetting button to relatch the starter unit.

In Figure 5 is shown a modified form of my improved attachment in which the starter casing is recessed or perforated approximately diametrically thereof to provide a pivotal mounting for the actuating member. The perforations 42, 43 are made preferably near the upper rim of the dish-shaped cap 1 where the casing has been stiffened in the forming process and wherein the ends 44, 45 of the actuating member are seated. A slightly offset loop 46 is provided as before to engage the resetting button 23 upon movement of the handle portion 39a, as before. From the foregoing it will be observed that there has been provided an attachment for the starters of fluorescent lamps which is easily manipulated despite the inaccessibility of such starters on the lamp brackets, is easy to install and may be rapidly and inexpensively manufactured.

It will also be noted that due to the rather sharp radius of curvature of the button engaging portion, the actuating member will be normally maintained in its operative position, and will readily return to such position after movement of the handle portion to engage the resetting button. Thus, there is no possibility of the resetting button being maintained in its depressed or resetting position.

I claim:

1. An attachment for fluorescent lamp starters of the plunger operated, manually reset type comprising a substantially flat bridge member bent into the shape of a U having a central portion extending laterally over said plunger and in-

wardly facing, curved terminal portions for gripping the starter casing and longitudinally spaced bearing surfaces in its intermediate portions, and a rod-like plunger actuating member extending laterally of said starter subjacent said central portion of the bridge member and pivotally mounted in the bearing surfaces of said bridge member, said actuating member having a central deformed portion movable to reset said plunger in one position of rotation of said actuating member.

2. An attachment for fluorescent lamp starters having an axially extending plunger of the manually reset type comprising a generally flat bridge member overlying said plunger, means for securing said bridge member to said starter, and a plunger actuating member having a handle portion extending in parallelism with the axis of said starter and an integral, transverse portion in parallelism with said bridge member and pivotally mounted on said bridge member in spaced relation from said plunger and movable into contact therewith upon rotation of said handle portion.

3. An attachment as defined in claim 2 wherein said transverse portion is laterally offset from said bridge member for the major portion of its length.

4. An attachment for fluorescent lamp starters of the plunger-operated, manually reset type comprising a single, elongated member bent intermediate its ends to provide a reinforced handle portion, an inwardly bent, remotely disposed, starter-engaging terminal portion, a similar terminal portion spaced from said handle portion and an intermediate portion movable into contact with said plunger.

5. In a fluorescent lamp fixture having a socket for a lamp starter mounted therein, and a pair of sockets so mounted as to provide substantial obstruction of the starter by the lamp when rested therein, an attachment disposable over said starter and operable from a position laterally offset from the position of said lamp, said attachment comprising an elongated rod-like member pivotally mounted relative to said starter, an integral handle portion extending from said rod-like member, and a central laterally offset portion selectively movable into and out of engagement with said starter upon rotation of said handle portion.

6. An attachment for fluorescent lamp starters of the plunger-operated, manually reset type comprising a single, elongated member bent intermediate its ends to provide a closed loop, handle portion, an inwardly bent, remotely disposed, starter-engaging terminal portion, a similar terminal portion spaced from said handle portion and an intermediate portion movable into contact with said plunger.
